UNITED STATES PATENT OFFICE.

GEORGE J. BUCKEYE, OF KANSAS CITY, MISSOURI, ASSIGNOR, BY MESNE ASSIGNMENTS, TO AUTOMOBILE COMBINATION LOCK AND CIRCUIT BREAKER COMPANY, A CORPORATION OF MISSOURI.

COMBINATION-LOCK AND CIRCUIT-BREAKER.

1,082,731.

Specification of Letters Patent. Patented Dec. 30, 1913.

Application filed August 21, 1911. Serial No. 645,068.

To all whom it may concern:

Be it known that I, GEORGE J. BUCKEYE, a citizen of the United States, residing at Kansas City, in the county of Jackson and 5 State of Missouri, have invented certain new and useful Improvements in Combination-Locks and Circuit-Breakers, of which the following is a specification.

This invention relates to improvements 10 in combination locks and circuit breakers, and embodies a combination of novel features hereinafter described, and particularly pointed out in the claims.

The primary object of the device is to 15 prevent unauthorized persons from closing the electric circuits of automobiles, so that they will be unable to operate an automobile provided with my device.

The device can be used to equal advantage 20 on electric-driven, or gasolene-driven automobiles, and in order that the invention may be fully understood, reference will now be made to the accompanying drawings, in which:

25 Figure 1 is a front elevation of the device. Fig. 2 is a rear elevation of the device with a back plate forming a part thereof, removed to show the interior mechanism. Fig. 3 shows a group of tumblers employed 30 in carrying out the invention. Fig. 4 is a vertical section on line IV—IV of Fig. 1, and Fig. 5 discloses one form of circuit to which my device is applicable.

Referring in detail to said circuit, 46 35 discloses a starting box; 30 and 31, the circuit breaker and its contact of my device, said contact being connected to the starting box by a wire 40; 49 and 50, a circuit breaker and its contact, controlled by a cam 40 on the engine shaft; 43 a wire connecting the contacts 31 and 50; 45 a magneto; 41 a wire connecting the circuit breaker 49, with said magneto; 47 a battery; 44 a wire connecting battery 47 and wire 41; 48 a manual 45 switch; 41^a and 44^a, contacts at the free terminals of wires 41 and 44, respectively; and 51, a push button for controlling communication between wires 41 and 43. The operation is substantially as follows: When the 50 parts are in the position shown on Fig. 5, impulses may be transmitted to the spark plug of the engine (not shown) by throwing switch 48 into engagement with contact 44^a. This will establish a circuit from

battery 47, through wire 44, switch 48, circuit box 46, wire 40, members 30, and 31, wire 43, push button 51, and from wire 41 to wire 44, back to the battery 47. By manipulating the push button 51 the necessary impulses are transmitted to the spark plug 60 until the engine is under way, after which the battery 47 is cut out and the magneto 41 cut in by throwing switch 48, into engagement with contact 41^a. Further manipulation of the push button 51, is unnecessary, as the circuit breaker 49, thereafter controls the transmission of impulses to the spark plug, said circuit breaker being vibrated by the cam on the engine shaft in the well known manner.

In constructing the lock, I employ a cylindrical casing 1, having an integral face 2, and a removable back-plate 3 normally held in position by two screws 4, the heads of which are countersunk in the back plate, 75 as shown by dotted lines, Fig. 4. The inner sides of casing 1 and back plate 3 are protected by insulations 5 and 6, to prevent short circuiting of the current hereinafter referred to. Back plate 3 is provided with 80 a pair of stud-bolts 7, adapted to extend through the dash-board of an automobile (not shown) and be secured by nuts 8, which may be hidden by the engine-hood of the automobile. By thus hiding nuts 8, it 85 will be exceedingly difficult for unauthorized persons to locate the same, and as screws 4 can not be removed from the back-plate until the device is taken from the dash-board, access can not be had to the interior of the casing containing the time-lock and circuit breaker mechanism.

Face 2 of casing 1 is provided with a concentric annular dial 9, which is countersunk in said face and consists, preferably, 95 of celluloid, or other light-colored material, so that the black graduations thereon can be readily distinguished.

10 designates a knob provided with a circular flange 11, and a stem 12. Flange 11 100 has a pointer 13 stamped in one side thereof to coat with dial 9, and the inner face 14 of said flange is concave to snugly fit the convex portion 15 of face 2. The highest point of the convex portion 15 extends beyond 105 face 2 to exclude rain from the interior of the casing, and the lowest portion extends below face 2 to receive the low peripheral

portion of flange 11, which has a marginal recess 11^a, to receive the adjacent edge of dial 9.

5 Stem 12 extends through the central raised portion of face 2 and is journaled in a bearing 16, extending inward from the inner side of face 2, the inner end of stem 12 being reduced to form a shoulder 17, and threaded to receive a pair of jam-nuts 18, 10 whereby a tumbler 19 is firmly locked against shoulder 17, so that it will turn with stem 12 and knob 10.

15 Knob 19 is provided with a laterally-extending eccentric-pin 20 adapted to coact with one side of an eccentric-pin 21, extending laterally from opposite sides of an intermediate tumbler 22, loosely-mounted on bearing 16 and having a peripheral notch 23. The side of pin 21 opposite from pin 20 is 20 adapted to coact with an eccentric-pin 24, extending laterally from a tumbler 25, loosely-mounted on bearing 16 and provided with a peripheral notch 26 adapted to register with the notch 23. Tumbler 19 has a low 25 radius 27, and a high radius 28, the lowest point of radius 27 being on a level with the bottom of notches 23 and 26, while radius 28 is on a level with the peripheries of tumblers 22 and 25 for a purpose which will herein- 30 after appear. Two washers 29 are employed to space tumblers 19 and 25 equal distances from the intermediate tumbler 22. The tumblers control the movable arm 30 of a circuit-breaker consisting of said movable 35 arm and a stationary contact 31, which latter is secured to a block of insulation 32, in casing 1. Arm 30 is pivotally-mounted upon a screw 33 and divided into two sections 34 and 35 by insulation 36 to prevent current 40 passing from section 34 to section 35, thence to the tumblers and other portions of the device, through the intermediary of a down-turned tooth 37 integral with section 35. Arm 30 is pressed toward contact 31 by a 45 spring 38, and provided at its forward portion with a binding-post 39 to secure the terminals of two circuit wires 40 and 41. Arm 32 has a binding-post 42, to receive the terminals of two circuit-wires 43 and 44. 50 Circuit-wire 41 leads to a magneto 45, circuit-wire 43 leads to a starting-box 46, and circuit-wires 40 and 44 also lead to the starting-box 46, wire 44 communicating with a battery 47. The magneto 45 and the start-

ing-box 46 are of ordinary type and connected in the usual manner to a spark-plug (not shown), a detail description thereof is deemed unnecessary.

In the drawing the circuit-breaker is shown closed. When it is desired to open the 60 circuit-breaker, tumbler 19 is turned until its high radius 28 passes beneath tooth 37 and raises the same out of the notches 23 and 26 of the tumblers 22 and 25, respectively. Knob 10 may then be turned to rotate the 65 tumblers 22 and 25 until their notches pass from beneath the tooth 37, so that the same may rest upon the peripheries of said tumblers, and thus support arm 30 out of engagement with contact 31. The circuit-breaker can not then be closed until the knob is properly manipulated to return the tumblers to the position shown in Fig. 2. Numerous combinations may be had by simply loosening nuts 18 and turning tumbler 19 70 to different points on stem 12.

75 While I have shown and described the device for use in controlling the circuit of an automobile, I, of course, do not wish to be limited to this use, since it is obvious the 80 device can be employed to advantage in opening and closing various kinds of circuits.

Having thus described my invention, what I claim and desire to secure by Letters Pat- 85 ent, is:

1. In combination, a device of the character described consisting of a casing, a circuit-breaker therein comprising a stationary arm and a movable arm, said movable arm 90 comprising two sections divided by non-conducting material, one of said sections having a tooth, tumblers to control said movable arm, and means for actuating said tumblers.

2. In combination, a device consisting of 95 a casing, a circuit interrupter therein comprising a stationary contact and a pivoted arm carrying a coöperating contact, said arm being provided with a tooth, and permutation tumblers mounted in said casing to 100 act with said tooth to control the movement of said arm.

In testimony whereof I affix my signature in the presence of two witnesses.

GEORGE J. BUCKEYE.
